UNITED STATES PATENT OFFICE.

SAMUEL F. GOLD, OF ENGLEWOOD, NEW JERSEY.

STEAM-HEATER.

SPECIFICATION forming part of Letters Patent No. 225,472, dated March 16, 1880.

Application filed July 14, 1879.

To all whom it may concern:

Be it known that I, SAMUEL F. GOLD, of Englewood, in the county of Bergen and State of New Jersey, have invented certain new and useful Improvements in Steam-Heaters for Warming and Ventilating Buildings; and I do hereby declare the following to be a full, clear, and exact description of the same, reference being had to the accompanying drawings, making part of this specification, in which—

Figure 1 of said drawings represents a fragmentary portion of a steam-pipe with coiled wire attached thereto. Fig. 2 is a central section of the same. Fig. 3 is a cross-section at the line x x of Fig. 1. Fig. 4 represents a ring having pins and slots for securing the wire coils. Fig. 5 represents a modification of my improvements, and consists in a series of 20 rings, with pins, upon a steam-pipe.

This invention relates to apparatus for warming and ventilating buildings by means of a current of air passing in contact with surfaces heated by steam, and has for its object the increase of the heating-surface of the pipes, thereby imparting a very much larger amount of heat to the air passing over them, being in effect equivalent to the multiplication of the length of the pipes used and the economization 25 of the space occupied by the heating-surface, as hereinafter more fully set forth.

To this end the said invention consists in providing a series of steam-pipes, (usually called a "box-coil,") as employed in steam-heating, and forming around each pipe of the same certain metallic surfaces, so arranged as to divide, subdivide, or split up the current of air in its passage upward around the pipes, whereby it is more perfectly heated.

40 To effect this result a coil of about one-half inch diameter, more or less, made of metallic wire, say No. 14, is formed into a double or compound coil, B, by being wound around the pipe A, which coil, by reason of its elastic force and spiral form, closely embraces and presses the pipe at every point of contact therewith.

By this arrangement of the coil close contact with the hot pipe is secured and a very 45 great length of extended wire surface may be

utilized. Necessarily a very large volume of heat must be conducted into the current of air passing through and over the coil.

By this form of construction the current of air is caused to pass nearly or quite around the 55 pipe, instead of being deflected from it, as it is from plain pipe, for it will be observed that when the air strikes the wires on the under side of the pipe it necessarily finds its freest passage upward through the circular channels 60 formed by the coils, and is therefore conducted around the pipe, bringing the entire surface of the pipe and the heated wire into action, whereby the air is more thoroughly heated.

By this construction fewer pipes can be used 65 in forming a heating-stack on account of the increase of surface by means of the wire coils, and, as an additional advantage of fewer pipes, the successful passage of steam through them is insured without danger of the freezing 70 of the water of condensation, which difficulty is apt to occur where large coils of pipe are used.

The rings C C are provided with slots and pins, which are used for securing the ends of 75 the wire coils, as seen at a, Fig. 4.

The rings are made adjustable and capable of being keyed fast at any desirable point along the pipe.

I am aware that coils of metallic wire have 80 been employed to enlarge the area of heating-surface, as set forth in Letters Patent of the United States granted to Edmund Russell, July 6, 1875, which shows coils of metallic wire introduced between loop-pipes, and also 85 a single wire wound around them; but these are not the features claimed in my invention.

Having thus described my invention, what I claim, and desire to secure by Letters Patent, is—

1. The combination of the steam-tube A with the compound coil B, substantially as shown and described.

2. The combination, with the steam-tube A, of the rings C and C and the compound coil 95 B, substantially as shown and described.

SAMUEL F. GOLD.
